Stoves and Ranges
Cooking Stoves and Ranges.

Design No. 379. —

Fig. 1.

Fig. 2.

Mr. G. Sanderson
Design for Cooking Stoves

Patented 3rd June 1853

Des. 379

Wm L. Sanderson, Troy, New York, assignor to R.R. Finch,
Pekskill N.Y. Letters Patent No. 379. Dated June 3, 1851.

The Schedule referred to in these Letters Patent, and making part of the same

To all whom it may concern:

Be it known, that I, Wm L. Sanderson, of Troy, in the County of Rensselaer, and State of New York have invented a new ornamental Design for Cooking Stoves; and I do hereby declare that the following is a full and exact description of the same, reference being had to the annexed drawings, making part of this Specification, in which

Fig: 1. is a front elevation of the Cooking Stove showing the design on one of the front fire doors —

Fig: 2. is a side elevation, showing the design on the oven door, the side fire door and on the body of the stove.

Similar letters of reference indicate corresponding parts in each of the two figs: —

A. (Figs. 1 and 2) represents a border with corner pieces placed around the panels of the fire and oven doors. this is exactly as represented in the Figures, on the oven door (seen in Fig. 2) it is represented on one side only it being unnecessary to continue it around the panel.

B (Fig. 1) represents a figure on the panel of

the fire door which is on the front of the stove, this may be described as being similar to a shell with two stems bearing leaves issuing from the top and three stems having small buds on them. An exact representation is given in the drawing.

C (Fig. 2) represents a figure on the panel of the side fire door very similar to that represented by B in Fig. 1, the only difference being in the omission of two small buds at the bottom of the shell & the stems at the top having fewer buds on them. This side fire door has the same border A; as the front fire door.

D, represents a figure on the oven door, this has two stems projecting from the top of a shell bearing leaves, and two similar stems projecting from the bottom, also two stems projecting from the top and bottom bearing buds, two small flowers are also attached to the top of the shell by stems with buds, and placed between the stems bearing the leaves— two stems bearing buds project from the shell.

E, E, E, E, represent a border formed of circular and diamond shaped links and corner pieces. This border is upon the side of the body of the stove exactly as represented in Fig. 2.

F, F, is a border on the lower part of the body of the stove; this is formed of figures composed of egg shaped prominences having portions of leaves at their sides, these figures are divided by three beads as represented in Fig. 2.

Only one of the fire doors on the front of the stove is represented with the design as both doors are precisely alike.

Both sides of the stove are alike with the ex

ception of the side fire door, this on one side is an imitation door but has the same design as the real door.

The border FF extends round the front of the Stove, its position is indicated by F' in Fig. 1.

What I claim as new and desire to secure by Letters Patent is

The border A, with its corner pieces, the figures B, C and D; the borders E, E, E, E, and F, F, said borders and figures being of the form and situated precisely as represented and described.
